SLIVER DELIVERY UNIT FOR STATIONARY
BALLING HEAD

Gianni Bider, Corso Matteotti 1A, Milan, Italy

Filed Jan. 17, 1955, Ser. No. 482,343

Claims priority, application Italy Dec. 18, 1954

3 Claims. (Cl. 242—54.4)

This invention concerns a ball delivery group with stationary head, for single or double pin-field gill boxes for combing and drawing of natural or artificial textile fibers, the delivery being designed for one ball and one sliver per head, or two balls and two slivers per head, or one ball and two slivers per head or two balls and four slivers per head.

It is known that in gill boxes operating at high speed winding on balls of slivers delivered by the draft rolls is obtained, for manufacturing reasons, by keeping stationary the take-up rolls of the balling head and by moving the slivers longitudinally by means of a to-and-fro motion to obtain the balls. This method causes the continuous variation of the distance between the draft rolls and the winding point of the sliver on the ball, variation that is much greater as the length of the ball increases.

If such a variation of distance is not continuously compensated it causes uncontrolled drafts on the delivered slivers, which are harmful to their evenness.

With the known systems of compensation the slivers are forced, during the run between the draft rolls and the take-up rolls, to follow complicated courses, with sudden inversions of direction that cause the rubbing of slivers. During the inversion of the course the slivers, by bending, cause the swelling of the fibers lying on the internal radius and a draft of the fibers lying externally. In addition to this inconvenience the rubbing of slivers causes an accumulation of static charges on the fibers.

These inconveniences are prevented by the unit according to this invention, which is substantially characterized by the fact that the sliver delivered by the draft rolls is condensed on a loose roll or on a guide and, hence, with a small deviation, it goes directly to the point of tangency of the ball roll with only one rectilinear path, the compensation of the variation of distance between draft rolls and ball roll being obtained automatically in every position and condition by the continuous movement of the deviation roll or guide, perpendicularly to its rotation axis.

The invention will be described with reference to the enclosed sketch and both description and sketch are not restrictive but are merely given as an example.

Fig. 1 is a side elevation of the preferred model of the unit;

Fig. 2 is a front view showing the movement of the sliver and of the false twist trumpet during the winding operation;

Fig. 3 is a plan view of a detail of the construction; and Fig. 4 is a side view, partly in section, of the detail shown in Fig. 3.

The above figures show the frame A of the machine. The sliver 1 delivered by draft rolls or sliver supplying means 2 is condensed on a loose roll 3 the arbor 4 of which is supported by an oscillating arm 3' secured by a pivoted joint 4" to the frame A, the axis of the joint being parallel to that of the deviation roll 3.

The sliver, the deviation of which on roll 3 is less

2

than a right angle, goes directly from the point of tangency with roll 3 to the point of tangency of the driving roll 20, with only one rectilinear path, through the false twist trumpet 6. The latter is supported by a bracket 7, fixed to a unit 8 fitted on a cylindrical rod 9 parallel to the rectilinear path of sliver 1. The forward end of the rod 9 is connected to the arm 3' by means of a yoke 10' the arms of which are connected to the arbor 4 that rotatably supports the roll 3 on the arm 3'. The base 10 of the yoke has an extension 10 which serves as a pivot pin that extends through the eye 9' of the forward end of the rod 9. The extension 10 is so arranged that the pivot axis about which the forward end of the rod 9 pivots is perpendicular to the rod 9 and lies in a plane perpendicular to the axis of the ball roll 5.

When the bracket 12 slides on a stationary cylindrical guide 13 which may be firmly attached to the machine frame, the axis of the trumpet 6 is moved in a plane tangent to roll 3 and of the ball roll 5. Because of rod 9 the axis of the trumpet is always incident to the axis of pivot 10 and therefore by arranging the latter in such a way as to correspond to the point of tangency of the sliver on roll 3, the trumpet 6 will always have the same direction as the rectilinear path 1 of the sliver, as shown in Fig. 2. Furthermore as the axis of pivot 11 is placed near the bottom end of the trumpet, this end will move along a line parallel to the axis of the ball roll 5.

During the transverse movement of the trumpet along the ball roll, guide 9 causes the roll 3 to oscillate around pivot 4" so as to keep constant the distance between the draft rolls and the ball roll. This is so inasmuch as during transverse reciprocation of the trumpet 6 (Fig. 2), the rod 9 will occupy different angular positions, and also the forward end of the rod 9 will be spaced different distances from the transverse plane within which the axis 11 is reciprocated. This simultaneous reciprocation and varying of the angular position of the rod 9 will bring about pivoting of the forward end of the rod 9 about the extension 10 as well as pivoting of the yoke 10' about the arbor 4 and pivoting of the arm 3' about the joint 4". Consequently, the roll 3 will, during reciprocation of the trumpet 6, swing along the arc indicated at X so that the length of the path along which the sliver moves from the supply rolls 2 to the ball roll 5 will be maintained substantially constant at all times. In this way, the tension on the sliver will remain substantially constant.

The lowest position 4' of the roll 3 (Fig. 1) will obviously be attained when the trumpet reaches its limit stop, i.e. the inversion of the traverse motion. In this way any variation of tension is prevented and therefore any draft of the sliver during its run from the draft rolls to the ball roll, which would effect its evenness, is avoided.

The rotation of trumpet 6 is obtained by means of a couple of cylindrical gears 14 and 15, the one keyed and the other one co-axial to rod 9. Gear 15 is fixed to a miter gear 16 meshing with another miter gear 17, freely rotatable on pivot 11.

A cylindrical toothed wheel 18 is secured to miter gear 17 to mesh with a rack 19 that is stationary and parallel to the guide 13 and to the axis of ball roll 5.

In this way the alternate motion of the bracket 12 along the pivot 13 causes the rotation of the trumpet 6 around its own axis. The position of the trumpet allows the distribution of the false twist in the whole length of the rectilinear path of sliver 1 between the points of tangency of rolls 3 and 5.

In practice the details of the construction of the unit may vary without deviating from the object of this invention and therefore from the patent.

I claim:

1. In a baller, in combination, elongated balling means

adapted to have wound thereon a sliver supplied substantially within a delivery plane; sliver supplying means spaced from said balling means and having a delivery point lying exteriorly of said plane; first sliver guide means for guiding substantially within said delivery plane the sliver supplied by said supplying means, said first guide means being arranged between said supplying means and said balling means and adjacent the latter for reciprocating movement relative thereto in the direction of the length thereof so that a sliver guided by said first guide means may be balled evenly onto said balling means, said first guide means during its reciprocating movement occupying different positions wherein the paths along which the sliver moves from said delivery point of said supplying means to the point at which it is wound upon said balling means tends to be of different lengths; second sliver guide means arranged in the region of said delivery plane between said delivery point of said supplying means and said first guide means for guiding the sliver supplied by said supplying means substantially into said plane, said second guide means being pivotable transversely to said delivery plane about a first pivot axis extending in the direction of said balling means so as to be capable of occupying different positions wherein the sliver moves along different paths forming different angles with said delivery plane; and connecting means interconnecting said first and second guide means for pivoting the latter transversely to said delivery plane in such a manner that during reciprocating movement of said first guide means, said second guide means moves throughout such positions as to guide the sliver along different paths forming such angles with said delivery plane that the length of the sliver path is maintained substantially constant at all times, said connecting means including an elongated connecting member connected at one end thereof to said first guide means for reciprocating movement therewith and for pivotal movement about

a second pivot axis normal to said delivery plane, said connecting member being connected at its opposite end to said second guide means for pivotal movement relative thereto about a third pivot axis also normal to said

5 delivery plane and for reciprocating movement relative to said second guide means in a direction coextensive with said third pivot axis, whereby said second guide means will, during reciprocating movement of said first guide means, pivot about said third axis, thereby moving 10 transversely to said delivery plane and guiding the sliver along different paths forming different angles therewith.

2. The combination defined in claim 1 wherein said first guide means includes a tubular member having an axis lying substantially within said delivery plane and 15 extending substantially parallel to said connecting member, said tubular member being pivotable with said connecting member about said second axis during reciprocating movement of said first guide means so that said tubular member occupies different angular positions relative to said balling means.

3. The combination defined in claim 2, and additional means for rotating said tubular member about its axis during reciprocating movement of said first guide means.
